SHEET HOLDER

Andrew J. Lev, Maple Heights, Ohio, assignor to
The Cleveland Pneumatic Tool Company,
Cleveland, Ohio, a corporation of Ohio

Application February 5, 1942, Serial No. 429,629

8 Claims.

(Cl. 85—5)

This invention relates to improvements in sheet holders, that is to say devices adapted to be inserted into certain of the registering rivet holes of a pair of sheets to be joined for holding the sheets together while rivets are being set in other registering holes.

One of the objects of the present invention is the provision of a holder of the character described which shall be of simple construction and relatively low cost and which shall be effective and certain in its operation.

Other objects and features of novelty will appear as I proceed with the description of that embodiment of the invention which, for the purposes of the present application, I have illustrated in the accompanying drawing, in which

Fig. 1 is a longitudinal sectional view of the holder with a fragmental illustration of a pair of pliers that may be used for operating the holder.

Fig. 2 is an elevational view of the holder only, looking in the direction of arrows 2—2 of Fig. 1;

Fig. 3 is a longitudinal sectional view showing the plungers depressed and in position to be projected through a pair of registering rivet holes:

Fig. 4 is a similar view showing the holder in operative position on a pair of sheets;

Fig. 5 is a cross-sectional view on a larger scale, the view being taken substantially on the line 5—5 of Fig. 1; and

Fig. 6 is a cross-sectional detail view on a still larger scale taken substantially on the line 6—6 of Fig. 3.

The device illustrated comprises a metal cup 10 with a central hole in the bottom thereof through which two plungers project, that is a long plunger 11 and a short plunger 12. The long plunger has an enlarged cylindrical portion 13 just below its head 14.

A coil spring 15 surrounds the plunger 11 and bears at its upper end against head 14 and at its lower end against the bottom of cup 10. The shank of plunger 12, when the latter is retracted, is also surrounded by the lower coils of spring 15, but at its upper end plunger 12 has an outward bend 16 which projects radially into the space between two adjacent coils of the spring at an intermediate point of the latter. When the spring is fully compressed as in Fig. 3, part of this bend 16 extends into a cavity 17 in the lower end of the cylindrical part 13 of the plunger 11.

The shanks of plungers 11 and 12 are flexible, and at their lower ends they carry feet 18 and 19 respectively which are of such size that when the plungers are retracted to the position of Fig. 1 or to that of Fig. 4 their combined cross-sectional area is greater than the cross-sectional area of the rivet holes 20 in a pair of sheets 21 to be joined. Preferably also the meeting surfaces of the feet 18 and 19 as well as of the shank

of plunger 11 are cam-shaped so that, when the feet approach each other after having been put into the relative positions illustrated in Fig. 3, retraction of the plungers, the long one faster than the short one, causes these cam surfaces to slide upon each other and swing the feet outwardly into the positions illustrated in Fig. 1 or 4, depending upon whether or not the plungers have been inserted through rivet holes in sheets to be joined. Normally the shanks of the plungers are bowed somewhat, as indicated in Figs. 1 and 3, in order to insure their coming together snugly at their lower ends, and when they have been projected through a pair of rivet holes and are retracted these bowed portions are straightened out more or less by the walls of the rivet holes, thus bringing the main portion of said shanks into an appressed relation and tending further to spread the feet 18 and 19.

The spring 15 is relatively stiff, and as is usual in devices of this sort, pliers are used to enable the operator to compress the spring. Such pliers are illustrated in Fig. 1 and comprise two parts 25 and 26 pivoted together at 27, the part 25 having a bifurcated jaw to straddle cup 10 and engage beneath the rim 28 thereof, while part 26 has a single jaw with a rounded face 29 for engagement with the head 14. In use, the holder is placed in the pliers in the manner illustrated in Fig. 1. The handles of the pliers are then brought together compressing the spring 15 as in Fig. 3 and projecting the plungers to the extent indicated in that figure. When still in the grip of the pliers, the plungers are then projected through the registering holes 20 until the cup 10 engages the uppermost sheet. Thereafter the operator relaxes his hold upon the pliers, permitting the spring to expand and draw the plungers upward until they assume the position of Fig. 4, when the feet engage the outer surface of the lower sheet 21 and act to compress the sheets tightly against the cup 10. The pliers may then be removed.

Having thus described my invention, I claim:

1. In a sheet holder, a cup the lower surface of which functions as an abutment for engagement with the outer surface of one of a pair of sheets to be joined, two plungers slideable through a bottom opening in said cup having feet with a combined cross-sectional area greater than that of the rivet holes in the sheets to be joined, means for moving the plungers differentially to cause one to project beyond the bottom of the cup a greater distance than the other, the shank of the former and the foot of the latter then having a combined cross-sectional area less than the cross-sectional area of said holes, whereby the plungers may be caused to extend through one of said holes, and spring means adapted to retract said plungers to bring both of said feet into

position against the outer surface of the other sheet to be joined.

2. In a sheet holder, a cup the lower surface of which functions as an abutment for engagement with the outer surface of one of a pair of sheets to be joined, two plungers slidable through a bottom opening in said cup having flexible shanks oppositely bowed and having feet with a combined cross-sectional area greater than that of the rivet holes in the sheets to be joined, means for moving the plungers differentially to cause one to project beyond the bottom of the cup a greater distance than the other, the shank of the former plunger and the foot of the latter one then having a combined cross-sectional area less than the cross-sectional area of said holes, whereby the plungers may be caused to extend through one of said holes, and spring means adapted to retract said plungers to bring both of said feet into position against the outer surface of the other sheet to be joined.

3. In a sheet holder, a cup the lower surface of which functions as an abutment for engagement with the outer surface of one of a pair of sheets to be joined, two plungers slidable through a bottom opening in said cup having flexible shanks and having feet with a combined cross-sectional area greater than that of the rivet holes in the sheets to be joined, means for moving the plungers differentially to cause one to project beyond the bottom of the cup a greater distance than the other, the shank of the former plunger and the foot of the latter one then having a combined cross-sectional area less than the cross-sectional area of said holes, whereby the plungers may be caused to extend through one of said holes, and spring means adapted to retract said plungers to bring both of said feet into position against the outer surface of the other sheet to be joined, said last named shank and foot having cooperating cam surfaces for deflecting at least one of said feet outwardly as the feet approach the sheets to be joined.

4. In a sheet holder, a cup the lower surface of which functions as an abutment for engagement with the outer surface of one of a pair of sheets to be joined, a long plunger with a head adapted to be engaged by a compressing tool, a shank projecting through an opening in the bottom of said cup and a foot below the bottom of the cup, a short plunger with a shank projecting through said opening and with a foot below the bottom of the cup, and a coil spring interposed between the bottom of the cup and the head of the long plunger, said short plunger engaging the spring at a point intermediate its ends, whereby depression of the long plunger causes depression of the short plunger at a slower rate, the combined cross-sectional area of the foot on the short plunger and the adjacent portion of the shank of the long plunger when the plungers are fully depressed being less than the cross-sectional area of the rivet holes of the sheets to be joined.

5. In a sheet holder, a cup the lower surface of which functions as an abutment for engagement with the outer surface of one of a pair of sheets to be joined, a long plunger with a head adapted to be engaged by a compressing tool, a shank projecting through an opening in the bottom of said cup and a foot below the bottom of the cup, a short plunger with a shank projecting through said opening and with a foot below the bottom of the cup, and a coil spring interposed between the bottom of the cup and

the head of the long plunger, said short plunger having an outwardly bent upper end extending between two adjacent coils of the spring intermediate the ends of the latter, whereby depression of the long plunger causes depression of the short plunger at a slower rate, the combined cross-sectional area of the foot on the short plunger and the adjacent portion of the shank on the long plunger when the plungers are fully depressed being less than the cross-sectional area of the rivet holes of the sheets to be joined.

6. In a sheet holder, a cup the lower surface of which functions as an abutment for engagement with the outer surface of one of a pair of sheets to be joined, a pair of plungers slidable through a bottom opening in said cup having flexible shanks oppositely bowed adjacent their lower end and having feet with a combined cross-sectional area greater than that of the rivet holes in the sheets to be joined, means for moving the plungers differentially to cause one to project beyond the bottom of the cup a greater distance than the other, the shank of the former and the foot of the latter then having a combined cross-sectional area less than the cross-sectional area of said holes, whereby the plungers may be caused to extend through one of said holes, and spring means adapted to retract said plungers to bring both of said feet into position against the outer surface of the other sheet to be joined.

7. In a sheet holder, a cup the lower surface of which functions as an abutment for engagement with the outer surface of one of a pair of sheets to be joined, a pair of plungers slidable through a bottom opening in said cup having flexible shanks oppositely bowed adjacent their lower end and having feet with a combined cross-sectional area greater than that of the rivet holes in the sheets to be joined, means for moving the plungers differentially to cause one to project beyond the bottom of the cup a greater distance than the other, the shank of the former and the foot of the latter then having a combined cross-sectional area less than the cross-sectional area of said holes, whereby the plungers may be caused to extend through one of said holes, and spring means adapted to retract said plungers whereby said bowed shanks will move into appressed relation as contact is made with the walls of said rivet holes to bring both of said feet into position against the outer surface of the other sheet to be joined.

8. In a sheet holder, a cup the lower surface of which functions as an abutment for engagement with the outer surface of one of a pair of sheets to be joined, two plungers slidable through a bottom opening in said cup having flexible shanks oppositely bowed and having feet with a combined cross-sectional area greater than that of the rivet holes in the sheets to be joined, means for moving the plungers differentially to cause one to project beyond the bottom of the cup a greater distance than the other, the shank of the former plunger and the foot of the latter one then having a combined cross-sectional area less than the cross-sectional area of said holes, whereby the plungers may be caused to extend through one of said holes, and spring means adapted to retract said plungers whereby said flexible shanks will move into appressed relation as contact is made with the walls of said rivet holes to bring both of said feet into position against the outer surface of the other sheet to be joined.
